(57) **CLAIM**

The ornamental design for a basting brush with contour grip, as shown and described.

DESCRIPTION

FIG. 1 is a front elevation view of a basting brush with contour grip showing my new design;

FIG. 2 is a top plan view thereof;

FIG. 3 is a bottom view thereof;

FIG. 4 is a right side elevational view thereof; and,

FIG. 5 is a left side elevational view thereof.

The rear elevational view comprises a mirror image of the front elevational view and the portions shown in dashed lines form no part of the claimed design.
